UNITED STATES PATENT OFFICE.

JAMES H. PAIGE, OF MANCHESTER, NEW HAMPSHIRE.

FRUIT-JAR CLOSURE.

1,276,103.

Specification of Letters Patent. Patented Aug. 20, 1918.

Application filed August 8, 1917. Serial No. 185,013.

To all whom it may concern:

Be it known that I, JAMES H. PAIGE, a citizen of the United States, residing at Manchester, county of Hillsborough, and State 5 of New Hampshire, have invented certain new and useful Improvements in Fruit-Jar Closures, of which the following is a specification.

This invention relates to a tension reserve 10 adjustable closure for fruit jars and is an improvement on fruit jar closures such as are set forth in the patent of H. W. Putnam, No. 256,857, April 25, 1882.

Considerable fruit is damaged through 15 insecure closure of the jars in the foregoing type of fruit jar. This is due to variation in the thickness of the rubber rings or gaskets, inequalities in the wires comprising the fastening means, and slack tension due 20 to various causes such, for instance, of wear, compression of the parts, bending of the wires, and lack of means to compensate, by adjustment, for these deficiencies as they arise.

25 My invention has for its object the provision of an improved tightening or closing means which can be quickly changed to enable any desired tension to be put upon the clamping or locking bail so that a reserve 30 of tension is at all times obtainable to adapt the fastener to properly clamp the glass top or closure on the jar.

My invention does away with the defects 35 heretofore existing in this general type of jar closures and renders it unnecessary to resort to extra rubber rings, pieces of cardboard or wood, or the like, to take up the slack brought about by causes heretofore enumerated.

40 In carrying out my invention, I provide the neck of the fruit jar with a plurality of inclined shoulders, and a rotatable, or rotarily shiftable yoke or band having inclined parts or sections respectively adapted 45 to coöperate with the inclined shoulders, the clamping and operating bails being carried by the ring or yoke, whereby the ring or yoke may be shifted to change, at will, the extremes or limits of the vertical movement of 50 the clamping bail so that the latter will exert any desired tension on the closure when the operating bail is pressed down. Preferably, the bails will be connected to clips or ears on the ring or yoke. If the ring or yoke is of 55 wire, it will be provided with crimps, humps

or shoulders to retain the ears. The jar is preferably provided with shoulders which join the terminus of one incline to the beginning of the next incline; and, the wire or yoke will have shoulders or abutments which 60 will be limited by the shoulders aforesaid to prevent too great backward movement of the yoke. The points of pivoting of the bails to the yoke are spaced apart by an arc of less length at one side of the jar than at the 65 other side so that these points will not lie in the same diameter of the jar.

The embodiment of the invention which is hereinafter set forth and shown in the accompanying drawings is to be considered as 70 illustrative, instead of restrictive, of the scope of the invention; as modifications may be resorted to without changing the principles of the invention.

In the accompanying drawings: 75

Figures 1 and 2 are opposite side elevations;

Fig. 3, is a front elevation; 80
Fig. 4, is a section on line 4—4, Fig. 3; and

Fig. 5, is a detail perspective of the band or yoke.

The fruit jar 1 is provided with a groove or rabbet 2, a rubber ring or gasket 3, and a glass closure or top 4, as usual. 85

The neck is provided with a plurality, preferably two, cam inclines 5 and 6. The beginning or origination 7 of each incline is connected to the terminus 8 of the other incline by a shoulder such as shown at 9 and 10. The angle of inclination of the shoulders 5, 6 is the same. 90

A band or yoke 11 encircles the neck of the jar and is rotatable therearound, said band being provided with inclined portions 12 and 13 respectively adapted to bear against the shoulders 5 and 6. The parts 12 and 13 are connected by shoulders or bends 14 and 15, respectively adapted to serve as abutments to engage the shoulders 9 and 10 to limit movement of the band or yoke, backwardly. Ears or clips 16 and 17 embrace the yoke or band and are held against slipping by the bends 18, in one instance, and by a bend 19 and the bent portion or shoulder 15, in the other instance. The clips are provided with holes 20, the distance between the holes 20 of the respective ears or lugs is less, when measured along an arc on one side of the jar than along an arc on the other side 110

of the jar. The holes 20 are not at ends of a diameter but are offset from a diameter.

The operating bail 21 has its pivotal ends 22 received in the holes 20 and it has bent 5 eyes 23 which receive the bent ends 24 of the locking bail 25. While the pivotal points of the operating bail are offset from a diameter, the locking bail 25 lies in diametrical relation to the jar by reason of the eyes 23 being 10 thus disposed.

When clamping the closure down on the jar, the diametrically offset arrangement of the pivots of the operating bail insures a firm locking of the fastener, once the operating bail has been pressed down.

By shifting or rotating the band or yoke 11 around the neck of the jar, the holes 20 which represent the pivotal points of the bails, are brought higher or lower, according 20 to the direction in which the band or yoke is turned. This is brought about by the engagement of the parts 12 and 13 with the cam inclines 5 and 6. Any desired tension can therefore be arranged for. Consequently, after use, if greater pressure or tension is needed to hold the closure on the gasket the band or yoke is rotated further and the locking bail will then properly hold the closure.

30 My invention provides for adjustment and reserve tension which takes care of inequalities due to manufacture and, also, to wear and existing conditions, insuring tight closure at all times.

35 I am aware that a band could be substituted for the wire in which event the clips or ears might be an integral part of the band and there would be no necessity for providing the retaining crimps or humps shown 40 which hold the clips against slipping.

Having thus described my invention what I claim as new, and desire to secure by Letters Patent, is:—

45 1. A fruit jar closure comprising a plurality of inclined cam shoulders on the jar, a yoke or band rotatably mounted around the jar having inclined parts corresponding to the shoulders and respectively adapted to

coöperate therewith, and a releasable top fastener carried by said yoke or band.

2. A fruit jar closure comprising a plurality of inclined cam shoulders on the jar, abutments connecting the beginning of one shoulder with the terminus of another shoulder, a yoke or band rotatably mounted 55 around the jar having a plurality of inclined parts corresponding to, and coöperating with the respective cam shoulders, the band having shoulders connecting its inclined parts which are adapted to engage the abutments 60 on the jar, and a releasable top fastener carried by said yoke or band.

3. A fruit jar closure comprising a plurality of inclined cam shoulders on the jar, a yoke or band rotatably mounted around 65 the jar having a plurality of inclined parts corresponding to the shoulders and adapted to coöperate with them, and a releasable top fastener pivoted to the yoke or band in the region of the highest points of the inclined 70 parts thereof.

4. A fruit jar closure comprising a plurality of inclined cam shoulders on the jar, a yoke or band rotatably mounted around 75 the jar having a plurality of inclined parts corresponding to the shoulders and adapted to coöperate with them, and a releasable top fastener pivoted to and carried by said yoke or band at points on opposite sides of the jar which lie in a line of less length than a diameter, being nearer to each other around one side of the jar than the other side of the jar.

5. A fruit jar closure comprising a plurality of inclined cam shoulders on the jar, a yoke or band rotatably mounted around 85 the jar having a plurality of inclined parts corresponding to the shoulders and adapted to coöperate with them, an operating bail pivoted to the yoke or band at points offset from a diameter of the jar, and a locking 90 bail adapted to engage the jar top, which is pivoted to the operating bail at points offset from the pivots of the latter.

In testimony whereof, I hereunto affix my signature.

JAMES H. PAIGE.
